UNITED STATES PATENT OFFICE.

JOHN FRANK TILLER, OF WASHINGTON, DISTRICT OF COLUMBIA.

DESIGN FOR A STATUETTE OR SIMILAR ARTICLE.

50,669.

Specification for Design.

Patented Apr. 24, 1917.

Application filed February 8, 1917. Serial No. 147,500. Term of patent 3½ years.

To all whom it may concern:

Be it known that I, JOHN FRANK TILLER, residing at Washington, in the District of Columbia, have invented a new, original, and ornamental Design for a Statuette or Similar Article, of which the following is a specification, reference being had to the accompanying drawing, forming part thereof.

The figure is a perspective view showing my new design.

The design consists of a cast or molded figure of a youth represented as walking on part of a globe and carrying a dove, and wearing a sash fastened by a safety-pin.

I claim:—

The ornamental design for a statuette or similar article as shown and described.

JOHN FRANK TILLER.
